METHOD OF MAKING A SPREADER

Lewis M. Elphinstone, Baltimore, Md.

Application December 5, 1932, Serial No. 645,666

4 Claims. (Cl. 29—148.3)

The object of my invention is an improved method of making a spreader, light and simple for vehicles.

A further object of my invention is an improved means or method for constructing a spreader in what I term unit construction.

A further object of my invention is the construction of units adaptable for assembling in a spreader.

10 With the foregoing and other objects in view, my invention consists of the novel construction, combination and arrangement of parts as hereinafter specifically described and illustrated in the accompanying drawing, wherein is shown the preferred embodiment of my invention, but it is understood that changes, variations and modifications may be resorted to which come within the scope of the claims hereunto appended.

15 In the spreading of materials it is necessary that an even distribution of the material shall be made over the surface to be spread. To accomplish that it is necessary that the construction of the spreader chute be such that 20 there is nothing thereon to cause a broken distribution, or a varying of the evenness of the flow of the material. I avoid all projections, or roughness in the construction of the various chutes, and so design the cross-section of the 25 chutes as to provide the proper delivery to the finishing flow.

30 In the drawing of the herein described embodiment of my invention: Fig. 1 is a plan view of my spreader attached to the rear of a truck body; Fig. 2 is a fragmentary end view in elevation of one side of the spreader; Fig. 3 is a view taken through 3—3 of Fig. 2, showing particularly how various sections of units of chutes are assembled; Fig. 4 is a view taken through 5—5 of Fig. 2, showing 35 particularly how the chutes are secured to the assembled angle iron, as shown, it is spot welded thereto, thus forming a unit construction of the spreader units.

40 45 Similar numerals refer to similar parts throughout the several views.

1 is a truck body containing the supply of material to be fed. 2 is the tail-gate of the truck body pivotally mounted at its top edge at 3. This tail-gate may be opened to any desired degree and held in position by its locking chains, not shown, the same being of the ordinary type of construction, and concerning which I claim nothing. 4 is the assembled spreader

50 which is attached to the truck body 1 by means of forward edge supporting chain 5 which chain is provided with hook 6 for attachment to the body and turnbuckle 7 which is attached to the forward edge of spreader 4 by means of U-bolt 8 secured to the eye of the turnbuckle 7. 9 is a brace secured to the truck body and to the forward edge of the spreader. 10 is an adjusting chain supporting the rear end of the spreader, and is attached to the spreader by U-bolt 11 similar to U-bolt 8, and is adjustable by 10 means of hook 12, as shown in Fig. 1. The sides of the spreader are secured to the opposite sides of the truck body as above described, the opposite site attachments being similarly numbered.

15 The spreader is provided with cross-wise supporting members 13 and 14; I have found that angle or T irons are suitable for this purpose. 15 are rectangular chute sections made integral with each other for the entire spreader, which I have found to be very satisfactory where material and appliances are available, but which, if desired, may be constructed in a plural number in a single unit, and these units secured together as shown in Fig. 4 at 16. In the drawing Fig. 2, I have shown two such units joined 20 together in the center at 16, each unit containing the necessary number of chutes integrally constructed to form the aggregate width of the spreader desired.

25 In the construction of these units, starting with a plain sheet of metal, what is known as a brake forms these units as shown in Fig. 3, said units containing the plurality of chutes being formed tapered, each chute being tapered to the front end as shown in Fig. 2, the desired degree 30 of taper being regulated by the requirements of the truck body and the width of the spreader desired. These chutes, or unit of chutes, are attached to supporting members 13 and 14 by some means that will not interfere with the interior surface of the chutes. I have found that spot welding on the under side of the chute to these members as shown at 17 is very satisfactory. I have also found that any good sheet metal 35 sufficiently hard to withstand wear, preferably of a noncorrosive character, is suitable for the forming of these chutes.

40 In Fig. 6 a modified shape of the chutes is shown as 18. These chutes shown have substantially a circular bottom with straight sides and are formed of individual units with a locking device 19 on one edge, the same locking over the plane edge 20 of the other edge of the adjacent chute. These chutes may be made in unit or 45 integral construction, as described for chutes 15, 50 55

either as a whole or in several sections for assembly in the spreader. Likewise, the chutes 15 may be made with similar attachments 19¹ locking over edge 20¹ where individual chute construction is desired, especially convenient for assembly purposes.

In the construction of the individual chutes or aggregation of sections of chutes, spot welding is resorted to where found to be desirable for structural purposes, such as maintaining position, for rigidity, etc. This applies to the edges 20, 20¹, 19 and 19¹, and also the attachment of supporting members 13 and 14 to the various chutes.

Referring now to the replacement or repair 15 elements shown in Figs. 8, 9 and 10, it has been found that the bottom of the chute, after being in use with hard material, becomes so worn that a new surface is required. This is supplied by repair member 21 formed to fit into the chute 20 either of rectangular or circular sections, and is locked over the edges of the old chute by locking member 22, which member 22 may consist of clips at spaced positions along the edge, or the entire edge. In certain classes of work it is desirable to fasten these repair members more securely, and for this purpose I have shown securing stud 23 at the upper or forward end of the chute and secured thereto to enter through opening 24 in the repair member and slip down 25 into a narrowed section thereof, thus locking the end of the repair member around stud 23. At the lower, or after end of the repair member secured to the chute is turn-back member 25 which embraces the lower end of the chute and 30 is sufficiently long to accommodate the slip of stud 23 in opening 24, thus securing the lower end of the repair member to the lower end of the chute. This is shown in Fig. 10.

At times it is desirable to prevent the flow 40 of material through certain sections of the spreader, or a number of the chutes, and for that purpose I have shown in Figs. 11, 12 and 13 a blanking gate 26 which registers with the cross-section of the chutes that it blanks. As 45 shown in Fig. 13 it is constructed for blanking a rectangular chute section such as shown in Fig. 3, it fitting over the sides of the chute and being secured in the spreader in position by means of rod 27 going through holes 28 in the 50 chutes and holes 29 in the blanking gate. This may be adjusted by means of the various holes 28 in the chute (see Figs. 11 and 12).

I have not shown the ordinary side plates used in a truck to prevent a leakage of material between the sides of the truck body and tail-gate, which ordinarily are plain metal plates slipped back to the tail-gate. Some truck tail-gates have triangular plates secured to the tail-gate and operating within the side bodies to prevent 55 the flow of material between the side body and tail-gate sidewise. I have not shown this, as I claim nothing concerning the same.

In some cases I have found it desirable to supplement or replace braces 9 by braces at the 60 center, or disposed along the forward edge, of my spreader, for attaching to the under-body of the truck, as convenience may dictate. To accomplish this I provide U-bolt 30 in supporting member 14; I show only one, and that is at the center, others may be provided. A brace 31 may be attached to this U-bolt, the other end of the brace being conveniently secured to the truck. These additional braces are occasionally found to be desirable where heavy material is being 65 spread and a light spreader is used, the spread-

ers being made of different gauge material of varying strength and weight as may be necessary to meet different kinds of work.

The operation of my invention is as follows:

My spreader is adapted for using almost any kind of material to be spread, hot, cold, wet or dry, fine or coarse. As an example, I will describe the spreading of pulverized cinders, more or less wet, used on an icy road, as that is rather an unusual condition and is being availed of at 10 this time.

The cinders, after being properly prepared and wet down, loaded from open bins and exposed to the weather, are contained in the body 1. The truck is tilted into position suitable for emptying by gravity. My spreader is adjusted to an angle with the floor of the truck to insure discharge of the material therefrom. This is usually parallel with the floor of the truck, but should sticking of the material be encountered 15 the spreader is slightly lowered at its after end.

The average width of the roads being constructed at this time is 18 feet. I have found that a spreader 8 1/2 feet wide at its after end will spread evenly a surface 9 feet wide; that is, 25 one-half of the width of the road to be covered. In the construction of wider or narrower roads not being a multiple of 9, a blanking of the spreader by means of spreading gate 20 will reduce the width of the spreader by blanking off 30 a number of the chutes to a point where the same is a multiple of the width of the road being spread.

Having thus described my invention, what I claim and desire to secure by Letters Patent is: 35

1. The process of forming a spreader provided with a plurality of chutes consisting of forming individual chutes by forming from a flat plate of metal double side walls by first making a bend in the metal to form a side wall, and at 40 a proper distance to form the height of the side walls doubling the metal back upon itself for a further distance to form a side wall, then bending the metal to form the bottom of the chute, then bending the metal to form a second side wall 45 at an angle from the bending of the metal to form the bottom above mentioned whereby a converging bottom with adjacent side walls is formed and, at a proper distance to form the height of the side wall, doubling the metal back 50 upon itself, the metal being spaced in its doubling back parallel the substantial thickness of said metal to permit an adjacent side wall to be introduced, the doubling back to form a securing element for an adjacent side wall and 55 means for securing a plurality of said chutes so formed together into a rigid structure.

2. The method of constructing spreader chutes and of securing a plurality thereof together consisting of, forming from a flat plate of metal substantially double side walls by first making a bend in the metal to form a side wall and at a proper distance to form the height of the side wall doubling the metal back upon itself for a further distance to form a side wall, then bending the metal to form the bottom of the chute, then bending the metal to form a second side wall at an angle from the bending of the metal to form the bottom above mentioned whereby a converging bottom with adjacent side 60 walls is formed, then welding the two side walls adjacent together at their bases on the exterior of the chute surface at the juncture thereat to 65 secure the same and prevent spreading of the side walls.

3. The method of constructing spreader chutes and of securing a plurality thereof together consisting of, forming from a flat plate of metal substantially double side walls by first making a bend in the metal to form a side wall, and at a proper distance to form the height of the side wall doubling the metal back upon itself for a further distance to form a side wall, then bending the metal to form the bottom of the chute, then at an angle with said bend, bend said metal up to form a side wall of a chute having converging sides, then at a distance sufficient to form the side wall again bend the metal back upon itself and proceed for the number of side walls desired, then welding the side walls together at their bases to secure the same and prevent spreading of the side walls by means of a cross-bar to which they are secured.

4. The method of constructing spreader chutes and of securing a plurality thereof together consisting of, forming from a flat plate of metal substantially double side walls by first making a bend in the metal to form a side wall, and at a proper distance to form the height of the side wall doubling the metal back upon itself for a further distance to form a side wall, then bending the metal to form the bottom of the chute, then at an angle with said previous bend, bending said metal up to form a side wall of a chute having converging sides, then at a distance sufficient to form the side wall further again bending the metal back upon itself and proceed for the number of side walls desired then securing the double side walls together.
